(57) **CLAIM**

The ornamental design for an overburden pilot bit, as shown and described.

DESCRIPTION

FIG. 1 is a top side perspective view of the first embodiment of my design an overburden pilot bit.

FIG. 2 is a bottom side perspective view of the overburden pilot bit shown in FIG. 1.

FIG. 3 is a side plan view of the overburden pilot bit shown in FIG. 1.

FIG. 4 is a bottom plan view of the overburden pilot bit shown in FIG. 1; and,

FIG. 5 is a top plan view of the overburden pilot bit shown in FIG. 1.

The broken lines in the drawings depict unclaimed environmental subject matter.
